UNITED STATES PATENT OFFICE.

WILLARD T. SEARS, OF HAMILTON, OHIO, ASSIGNOR TO PRATT & WHITNEY COMPANY,
OF HARTFORD, CONNECTICUT, A CORPORATION OF NEW JERSEY.

RADIAL DRILL.

1,076,242.

Specification of Letters Patent.

Patented Oct. 21, 1913.

Application filed March 27, 1913. Serial No. 757,129.

To all whom it may concern:

Be it known that I, WILLARD T. SEARS, a citizen of the United States, residing at Hamilton, in the county of Butler and State 5 of Ohio, have invented certain new and useful Improvements in Radial Drills, of which the following is a specification.

This invention relates to radial-drills, one of the objects of the invention being the 10 provision of means which is certain, positive and effective in operation by which the simultaneous shifting of two mechanisms (one or both of which may be manually governed) into working relation is prevented.

15 In the drawings accompanying and forming part of the present specification I represent in detail one of the several convenient forms of embodiment of the invention, which to enable those skilled in the art to practise the same will be set forth fully in 20 the following description. I do not restrict myself to this showing; I may depart therefrom in several respects within the scope of the invention defined by the claims following 25 said description.

Referring to said drawings: Figure 1 is a top plan view partly in section, of a radial-drill involving my invention. Fig. 2 is a side elevation partly in section of the same. 30 Figs. 3 and 4 are vertical sectional views of clamping means, in two different positions. Figs. 5 and 6 are detail views in elevation of an operating lever hereinafter more particularly described. Figs. 7 and 8 are horizontal sectional views of the parts shown in Figs. 3 and 4 and in positions corresponding 35 respectively therewith. Fig. 9 is a section on the line 9-9 of Fig. 2 looking in the direction of the arrow.

40 Like characters refer to like parts throughout the several figures of the drawings, which it will be seen are on different scales.

A radial drill ordinarily involves a column 45 which in practice rises from and is fastened to a base. In the drawings the base has been omitted, although a column which answers my requirements is shown, being denoted in a general way by 2. On 50 the front of the column is a horizontal arm 3 which supports the head which in turn carries the spindle. The said head and spindle are not, however, illustrated. Upon the back of the column is a bracket 4, the arm 55 and bracket 4 being connected rigidly to-

gether by the tie member 5 which extends through the space between the sections of the column, the latter having ways to support and guide the arm 3 and bracket 4 for vertical adjustments, the tie member 5 partaking of this movement. The bracket 4 sustains the motor 6 which is adapted to drive through interposed gearing, the shaft 7. The foregoing is a brief description of the radial drill set forth in my copending 60 application Serial No. 725,416, filed October 12, 1912, and the improvements are especially well adapted for incorporation in this particular machine, although as will be evident they can be employed with equal utility 65 in other connections. It will be remembered that in said prior application said shaft 7 is adapted through the intervention of suitable means, for rotating the drill-spindle. The armature shaft 8 has a pinion 9 fastened 70 thereto in mesh with the spur gear 10 fixed to the shaft 11 which in turn has fastened to it the pinion 12 in mesh with the spur gear 13 tight on the shaft 7. It will, therefore, be clear that when the armature shaft 8 is rotated, the shaft 7 and shaft 11 through the intermediate train of gears just described will be rotated as will also the drill-spindle. 75

As I have already stated one of the principal objects of the invention is the provision of means by which the simultaneous movement of a plurality of mechanisms, at least one of which is manually operable into working relation, will be positively precluded. In the present organization both of said mechanisms are manually operable, and although they may perform any function, one of the mechanisms actuates clamping means for the vertical adjustable arm 3, while the other throws into and out of action the adjusting mechanism for said arm, the construction being such that the mechanism for raising by power, said arm 3 cannot be in action while the head is clamped and vice versa. It will be clear that the clamping and adjusting means may vary radically as to character, although those shown have been found satisfactory and will hereinafter be described. 80

Within the column 2 is a rotary feed-screw 14 which is immovable in the direction of its longitudinal axis and also prevented from rotating as quite common in this art. This feed screw 14 extends through a co- 85

100

105

110

operating nut 15 supported in the arm 3. It will be clear that if the nut 15 be rotated the arm 3 will be raised or lowered depending upon the direction in which said nut is turned, provided said head 3 be in unclamped condition. If said arm be not unclamped it cannot thus be adjusted.

Fastened to the shaft 16 supported for oscillation by suitable bearings on the bracket 4, is the hand lever 17 by which said shaft 16 can be rocked. Said shaft 16 has at its inner end the eccentric stud 18 fitting a notch or slot 19 in the bar 20 slidably supported by bearings upon the tie member 5.

Fastened to the bar 20 is the collar 21 having a finger or projection 22 to enter a peripheral groove or channel in the clutch member 23 splined to the shaft 11 and co-operative with the clutch member 24 rigid with the worm 25, the nut 15 having a worm gear 26 engageable by said worm. The nut is carried in bearings 52 which is a part of the tie member 5 a collar 50 threaded on the nut holding said nut in place. In Fig. 2 the clutch member 23 is out of engagement with the clutch member 24 at which time the worm gear 26, nut 15 and arm 3 are at rest. It will be assumed that it is desired to adjust said arm and that the controlling mechanism is in such relation to permit the same. In this case the lever 17 is swung up thereby rocking the shaft 16 and through the stud 18 thrusting the bar 20 forward, so that the collar 21 will push the clutch member 23 into engagement with the companion clutch member 24 whereby through the connections described the worm 25 will be rotated to rotate the worm gear 26 and consequently the nut 15 to effect the adjustment of the arm 3.

Set into grooves formed at the junction of the column 2, bracket 4 and tie member 5 are the complementary clamping members 27 which as will hereinafter appear move up and down with the bracket 4 and connected arm 3 and which also engage against the column 2 when it is desired to hold the arm 3 in an adjusted position. Extending through these clamping members 27 are the rods 28, each rod at one end being provided with holding and check nuts 29 and prevented from revolving by any suitable means, while their other ends are furnished with adjusting nuts 30 constituting the hubs of hand levers 31 which hand levers have two positions, an ineffective or non-clamping position as shown in Figs. 4, 5 and 7 and a clamping position as shown in Figs. 1, 3, 6 and 8.

Co-operative with the nuts 30 and necessarily the hand levers 31 and also co-operative with the hand lever 17 is a controlling member hereinafter described which controlling member has two positions being adapted when in one of said positions to permit the

setting of the clamping members 27 through the action of the levers 31 and simultaneously to prevent the movement of the hand lever 17, while when in the other position said controlling member permits the movement of the lever 17 but prevents the setting of either or both clamping members, so that when said controlling member is in said first position, the arm 3 can be raised or lowered but not clamped, and when in said second position, said arm can be clamped but cannot be raised or lowered, the said controlling member, therefore, acting as an interlock.

A controlling member which answers my requirements is such a one as that denoted in a general way by 32, being shown as consisting of an elongated plate having longitudinal slots 33 near its terminals to receive the rods 28, said terminals being situated between the adjusting nuts 30 and the laterally enlarged portions 34 of the clamping members 27. The outwardly projecting parts of the enlarged portions 34 have the vertical faces 35 and 36 and the connecting oblique face 37, the faces 36 being back of the faces 35. The adjacent portions of the terminals of said controlling or interlocking members 32 have the vertical faces 38, 39 and 40 connected by short oblique faces 41 and 42, the face 38 being forward of the face 39 and the face 39 being forward of the face 40. In Fig. 4 the controlling or interlocking member 32 is shown as being in its elevated position, the upper walls of the slots 33 being above the rods 28 and there being a space or interval between the terminals of said controlling member and the enlargements 34, the hand levers 31 at this time extending upward as shown in said Fig. 4 and also in Fig. 5. Therefore, if said hand levers 31 be swung down through a quarter of a circle, they cannot operate the clamping device 27 an extent sufficient to set the same owing to the fact that the thinner ends of said controlling member 32 are opposite the enlargements 34. If the controlling members 32, however, be drawn downward so that their thick portions fill the spaces between the nuts 30 and the enlargements 34, the clamps 27 can be set when the levers 31 are drawn downward. The nuts 30 are peripherally cut away or segmentally slotted as at 43 to receive the stationary stops 44 on the bracket 4, one end wall of each slot 43 engaging the co-operating stop 44 when the lever 31 having the same is in one position, while the other end wall of said slot engages said stop when said lever is in the other position, the slots being of such length as to permit only a quarter of a turn of said hand levers 31. The hand lever 17 has a crank portion 45 connected by a link 46 with the controlling member or bar 32. In Fig. 2 the arm 3 is clamped in an adjusted position, the two levers 31 at 180

this time being in their set positions and the upper ends of the slots 33 being against the rods 28. When the arm 3 is clamped it will be clear that the controlling member 32 is also clamped, so that should any attempt be made to shift the lever 17 by hand, such shifting cannot be accomplished, owing to the fact that said controlling member 32 is locked firmly and substantially against movement. Before the controlling member and therefore the lever 17 can be shifted, it will be necessary to swing the levers 31 up and on the conclusion of such movement the member 32 is released, so that the lever 17 can be then swung up to throw the clutch member 23 into engagement with the clutch member 24 as already described. As the lever 17 is elevated to effect the engagement between these two clutch members the controlling member 32 is by reason of its link connection with said lever 17 elevated to a position where the arm 3 cannot be clamped.

What I claim is:

1. In a radial drill, the combination of a vertically adjustable arm, adjusting means for said arm, clamping means for said arm, and mechanism for preventing the operation of one of said means when the other is in operation.
  2. In a radial drill, the combination of a vertically adjustable arm, adjusting mechanism for said arm, clamping mechanism for said arm, and mechanism for positively preventing the operation of each of said first mentioned mechanisms when the other is in operation.
  3. In a radial drill, the combination of a vertically adjustable arm, mechanism for adjusting said arm, means comprising a lever adapted on its movement, to throw said adjusting mechanism into operation, clamping mechanism for the head, means comprising a lever, adapted on its movement to set said clamping mechanism, and means co-operative with the two levers for preventing simultaneous operating movements thereof.
  4. In a radial drill, the combination of a vertically adjustable arm, adjusting mechanism for said arm, mechanism including a manually operable member, adapted for throwing said adjusting mechanism into action, clamping mechanism for the head, mechanism including a manually operable member adapted on its movement to set the clamping mechanism, and means co-operative with the manually operable members for preventing simultaneously their operating movements.
  5. In a radial drill, the combination of a vertically adjustable head, a clamping member, a manually operable member co-operative with said clamping member, a device
- between said manually operable member and clamping member, having two positions being adapted when in one of said positions to permit the setting of the clamping member by said manually operable device and when in the other position to prevent the setting of said clamping member by said manually operable member, adjusting mechanism for said arm, a manually operable member shiftable from an operative to an inoperative position and from an inoperative to an operative position, means actuated by said manually operable member for throwing the adjusting mechanism into action on the movement thereof from an inoperative to operative position and for throwing said adjusting mechanism out of action on the movement thereof from operative to inoperative position, and a connection between said second manually operable member and said device for shifting the latter into clamped non-setting position when said second manually operable device is in operative relation and for shifting said device into clamped setting relation when said second manually operable device is in operative relation and for shifting said device into clamped setting relation when said second manually operable device is in inoperative relation.
6. In a radial drill, the combination of a vertical column in laterally separated sections, a drill supporting arm adjustably fitted against the sections of the column, a driving device for the drill located at the side of the column opposite that against which said arm fits, operative connections between said driving device and the arm, adjusting means for said arm, clamping means for said arm, and mechanism for positively preventing the operation of each of said means into operation when the other is in operation.
7. In a radial drill, the combination of a vertical column in sections, a vertically adjustable arm having a bearing engagement with the sections of the column, clamping means for the arm, comprising separate clamping devices co-operative with the respective sections of the column, adjusting mechanism for said arm, and mechanism for preventing the operation of the clamping mechanism when the adjusting mechanism is in operation and for preventing the operation of the adjusting mechanism when the clamping mechanism is in operation.
- In testimony whereof I affix my signature in presence of two witnesses.
